LATCH MECHANISM

George E. Dath, Mokena, Ill., assignor to Enterprise Railway Equipment Company, Chicago, Ill., a corporation of Illinois

Application March 11, 1954, Serial No. 415,465

6 Claims. (Cl. 105—308)

This invention relates, generally, to latch mechanisms for doors for load containing hoppers, and it has particular relation to latch mechanisms for wedging the door closed.

Among the objects of this invention are: To provide for wedging to closed position in a new and improved manner a door that is held in partly closed position by a latch bar; to lock the latch bar in the position where it holds the door closed; to provide a locking dog having one portion for positioning between the latch bar and the shoulder of a cooperating keeper to hold the door closed and another portion for holding the latch bar in the door closing position; and to provide complementary wedging surfaces on the latch bar and locking dog in order to facilitate entry of the one portion of the dog between the latch bar and the shoulder of the keeper.

Other objects of this invention will, in part, be obvious and in part appear hereinafter.

This invention is disclosed in the embodiment thereof shown in the accompanying drawings, and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following detailed description, taken together with the accompanying drawings, in which:

Figure 1 is a view, in side elevation, of a railway car hopper arranged to be closed by a door to which is applied a latch mechanism embodying the present invention;

Figure 2 is a view, partly in vertical section and partly in elevation, showing the hopper and door construction of Figure 1, the view looking from right to left;

Figure 3 is a view, in front elevation, of the lower portion of the door shown in Figure 2, the latch mechanism being shown in the position where the latch bar has been released from the shouldered keeper;

Figure 4 is a view, similar to Figure 3, but showing the locking dog in position where it is being cammed into a location between the latch bar and the shoulder of the keeper;

Figure 5 is a vertical sectional view, taken generally along the line 5—5 of Figure 3; and showing the locking dog in the released position;

Figure 6 is a view, similar to Figure 5, but showing the locking dog in the locking position with the door fully closed;

Figure 7 is a view, in side elevation, of the locking dog shown in the preceding figures, the locking dog being shown at an enlarged scale;

Figure 8 is a bottom plane view of the locking dog shown in Figure 9;

Figure 9 is a view, in front elevation, of the locking dog; and

Figure 10 is a view, in side elevation, looking from right to left of Figure 9 to illustrate further the details of construction of the locking dog.

2

Referring now particularly to Figures 1 and 2 of the drawings, it will be observed that the reference character 10 designates generally a hopper, such as a load containing hopper of a railway car. The hopper 10 is positioned between a longitudinally extending center sill 11 and a car side wall 12. The hopper 10 is formed by an upper floor 13 and a lower floor 14 and by an outer inclined side wall 15 and an inner vertical side wall 16. The hopper 10 is arranged to discharge through a hopper opening that is indicated, generally, at 17 in Figures 5 and 6 and is surrounded by a frame that is indicated, generally, at 18. Three sides of the frame have a generally T-shaped cross section. The frame 18 is secured in position on the hopper 10 by rivets 19. It includes a top frame member 20 that is secured to the upper floor 13 by rivets 21. Projecting laterally from the top frame member 20 are hinge butts 22 carrying hinge pins 23 on which hinge straps 24 are mounted. The hinge straps 24 are secured by rivets 25 to a door that is indicated, generally, at 26 and is arranged to close the opening 17 from the hopper 10 in accordance with conventional practice.

Near the lower central portion of the door 26 is an opening 29 through which a nose portion 30 of a shouldered keeper 31 projects. The keeper 31 has a base portion 32 that is secured by rivets 33 to the lower floor 14 and lowermost portion of the frame 18. The nose portion 30 has an inclined runway 34 for cooperating with the underside of a latch bar 35 to lift the same to a position where it can ride over an inclined surface 36 and engage a shoulder 37 of the keeper 31 for holding the door 26 in a partly closed position. The position of the shoulder 37 is such that, when it is engaged by the latch bar 35 there remains about one inch of movement of the swinging edge of the door 26 to close it.

As shown more clearly in Figures 2, 3 and 4 of the drawings, the latch bar 35 is pivotally mounted at 39 to swing in a plane parallel to the plane of the door 26 on a door beam casting, shown generally at 40, which is secured by rivets 41 to the front side of the door 26. The door beam casting 40 has an opening 42, Figures 5 and 6, which registers with the opening 29 in the door 26 to permit the nose portion 30 to project therethrough for cooperation with the latch bar 35.

Formed integrally with the door beam casting 40 near the left-hand end, as viewed in Figure 1, are an inner guide arm 43 and an outer guide arm 44 between which the end of the latch bar 35, remote from the pivot 39, is guided. Near the base of the outer guide arm 44 is a fulcrum ledge 45 while a fulcrum ledge 46 projects from the top. These ledges 45 and 46 are arranged, as described hereinafter, to receive a removable operating bar which is arranged to bear against one or the other and against a shoulder 47 formed integrally with and extending laterally from the latch bar 35. The fulcrum ledge 46 also is arranged to cooperate with a removable bar for operating a locking dog which also will be described.

Also formed integrally with the door beam casting 40 are an inner bracket member 50 and an outer bracket member 51, both being centrally positioned above the opening 42 and in alignment with the nose portion 30 of the shouldered keeper 31 as seen more clearly in Figures 2, 3 and 4 of the drawings. Formed integrally with the outer bracket member 51 at the upper end is a fulcrum boss 52 that is arranged to receive one end of a removable bar. A rivet 53 extends through the fulcrum boss 52, upper ends of the bracket members 50 and 51, and the door 26 for pivotally mounting a pivot portion 54 of a dog that is shown generally at 55 and the details of construction of which are shown more clearly in Figures 7, 8, 9 and 10 of the drawings. As there shown the pivot portion 54 has a hole 56 therein through which the rivet

53 can extend. The lowermost portion 57 of the dog 55 has a wedging surface 58 that is arranged to cooperate with a complementary wedging surface 59 on the latch bar 35 to facilitate entry of the lower portion 57, as shown in Figure 6, between the forward side of the latch bar 35 and the shoulder 37 of the keeper 31. The purpose of this is to effect the movement of the door 26 from a partly closed position shown in Figure 5 to the fully closed position shown in Figure 6.

With a view to locking the latch bar 35 in the door closed position, shown in Figure 6, the dog 55 is provided with a circular cam surface 60 with the center of curvature being the center of the hole 56. The cam surface 60 is formed on the underside of an upper portion 61 of the dog 55 which, as shown in Figures 7 and 10 of the drawings, is offset inwardly toward the door 26 from the lower portion 57. The cam surface 60 is arranged to engage the upper side 62 of the latch bar 35 for holding the latter in the door closed position. The dog 55 has a boss 63 formed integrally therewith for receiving a removable bar to operate the dog 55 from and to the locking position. A cross bar 64, Figures 3 and 4 of the drawings, extends between the upper ends of the bracket members 50 and 51 to brace them and also to provide a stop for the dog 55 in the unlatched position shown in Figure 3.

Assuming that the latch bar 35 is in the door closed position as shown in Figures 2 and 6 of the drawings, a removable bar, shown at 65 in Figure 2, is positioned on the fulcrum ledge 46 and underneath the boss 63 on the dog 55. The outer end of the bar 65 then is moved downwardly to raise the boss 63 and swing the dog 55 in a clockwise direction from the position shown in Figure 6 where it interfits between the front side of the latch bar 35 and the shoulder 37. When this has been accomplished the door 26 swings to a partly open position where the latch bar 35 rests against the shoulder 37. In this position, the swinging edge of the door 26 is spaced about one inch from the hopper 10. The locking dog 55 is swung to the position shown in Figure 3 where it rests against the cross bar 64.

Next the removable bar is positioned as indicated at 66 in Figure 2 underneath the shoulder 47 and on top of the fulcrum ledge 45. An upward thrust applied to the outer end of the bar 66 lifts the latch bar 35 from engagement with the shoulder 37 and permits the door 26 to swing to the pendant open position under the influence of gravity and as caused by the discharge of lading through the hopper opening 17.

When it is desired to close the door, it is made certain that the dog 55 occupies the position shown in Figure 3. Then the door 26 can be slammed shut. As the lower side 67 of the latch bar 35 engages the inclined runway 34, the latch bar 35 is deflected upwardly until it reaches the inclined surface 36 whereupon it moves downwardly under the influence of gravity to a position in engagement with the shoulder 37. As described hereinbefore, the door 26 now is held in a partly closed position. Next the locking dog 55 is swung manually from the position shown in Figure 3 to the position shown in Figure 4 and the removable bar is positioned as indicated at 68 between the boss 63 on the dog 55 and the fulcrum boss 52 on the outer bracket member 51. By swinging the bar 68 in a counterclockwise direction, the wedging surface 58 engages the complementary wedging surface 59 on the latch bar 35 and the dog 55 is swung in a counterclockwise direction to the position shown in Figure 6 where the lower portion 57 is interposed between the latch bar 35 and the shoulder 37. In this position the circular cam surface 60 engages the upper side 62 of the latch bar 35 and holds it in the latched position.

Since certain changes can be made in the foregoing construction and different embodiments of the invention can be made without departing from the spirit and scope

thereof, it is intended that all matters shown in the accompanying drawings and described hereinbefore shall be interpreted as illustrative and not in a limiting sense.

What is claimed as new is:

1. For combination with a hopper having a discharge opening, a pivotally mounted door for closing said opening, a shouldered keeper carried by said hopper, a latch bar pivotally mounted on said door to swing in a plane parallel thereto for engaging the shoulder of said keeper to hold said door partly closed, and a dog pivotally mounted on said door to swing in a plane parallel thereto, said dog having a portion swingable to a position between said shoulder and said latch bar to hold said door in the fully closed position and another portion for engaging said latch bar to hold the same in the latched position.

2. For combination with a hopper having a discharge opening, a pivotally mounted door for closing said opening, a shouldered keeper carried by said hopper, a latch bar pivotally mounted on said door to swing in a plane parallel thereto for engaging the shoulder of said keeper to hold said door partly closed, and a dog pivotally mounted on said door to swing in a plane parallel thereto, said dog having a portion with a wedging surface to engage said latch bar and facilitate entry between the same and said shoulder to hold said door in the fully closed position and another portion for engaging said latch bar to hold the same in the latched position.

3. For combination with a hopper having a floor and a discharge opening, a door pivotally mounted along its upper edge to swing from a pendant open position to an inclined position for closing said opening, a shouldered keeper carried by the floor of said hopper and adapted to project through an opening in the lower portion of said door centrally thereof when the same is closed, a latch bar pivotally mounted on said door to swing downwardly in a plane parallel thereto for engaging the shoulder of said keeper to hold said door partly closed, and a dog pivotally mounted on said door above said keeper to swing in a plane parallel thereto, said dog having a portion swingable to a position between said shoulder and said latch bar to hold said door in the fully closed position, and another portion for engaging said latch bar to hold the same in the latched position.

4. For combination with a hopper having a floor and a discharge opening, a door pivotally mounted along its upper edge to swing from a pendant open position to an inclined position for closing said opening, a shouldered keeper carried by the floor of said hopper and adapted to project through an opening in the lower portion of said door centrally thereof when the same is closed, a latch bar pivotally mounted on said door to swing downwardly in a plane parallel thereto for engaging the shoulder of said keeper to hold said door partly closed and a dog pivotally mounted on said door above said keeper to swing in a plane parallel thereto, said dog having a portion swingable to a position between said shoulder and said latch bar to hold said door in the fully closed position and another portion for engaging said latch bar to hold the same in the latched position, said one portion being positioned below and offset outwardly from said other portion when said dog is swung to locking position.

5. For combination with a hopper having a floor and a discharge opening, a door pivotally mounted along its upper edge to swing from a pendant open position to an inclined position for closing said opening, a shouldered keeper carried by the floor of said hopper and adapted to project through an opening in the lower portion of said door centrally thereof when the same is closed, a latch bar pivotally mounted on said door to swing downwardly in a plane parallel thereto for engaging the shoulder of said keeper to hold said door partly closed, and a dog pivotally mounted on said door above said keeper to swing in a plane parallel thereto, said dog having a

portion with a wedging surface to engage said latch bar and facilitate entry between the same and said shoulder to hold said door in the fully closed position and another portion for engaging said latch bar to hold the same in the latched position.

6. For combination with a hopper having a floor and a discharge opening, a door pivotally mounted along its upper edge to swing from a pendant open position to an inclined position for closing said opening, a shouldered keeper carried by the floor of said hopper and adapted to project through an opening in the lower portion of said door centrally thereof when the same is closed, a latch bar pivotally mounted on said door to swing downwardly in a plane parallel thereto for engaging the shoulder of said keeper to hold said door partly closed, and a dog 15 pivotally mounted on said door above said keeper to

swing in a plane parallel thereto, said dog having a portion with a wedging surface to engage a complementary wedging surface on said latch bar and facilitate entry between the same and said shoulder to hold said door in the fully closed position and another portion for engaging said latch bar to hold the same in the latched position.
